PLEATED TROUSERS

Solomon Sidney Shulkind, 5 Mancroft Court, Queens
Mead, St. John's Wood Park, London, England

Filed Jan. 29, 1963, Ser. No. 73,362

Claims priority, application Great Britain Aug. 1, 1962

Term of patent 14 years

(Cl. D3—17)

Fig. 1.

Fig. 2.

Fig. 3.

FIGURE 3 is a side view thereof with the waist band in an extended position, the side opposite being substantially similar thereto;

FIGURE 6 is a fragmentary view of the waist portion of the trousers showing the waist band and adjoining area of the leg portion in the non-extended position.

My design comprises a pair of pleated trousers of the configuration disclosed having all-over closely set box pleats extending throughout the entire length, substantially as shown in full lines.

I claim:

The design for pleated trousers, as shown and described.
